Filed Nov. 22, 1957, Ser. No. 698,309

Claims priority, application Germany Mar. 29, 1957

2 Claims. (Cl. 229—5.5)

The present invention relates to shipping, storage and like containers or receptacles.

Containers and receptacles heretofore utilized for purposes of shipping or storage have been cylindrical or circular in cross-section, this having been the simplest and inexpensive solution available under the prior art container manufacturing processes. However, circular containers take up excessive space during transportation and storage with the result that transportation and storage costs are relatively high.

A primary object of the present invention is to provide means facilitating the manufacture of sturdy paper- or cardboard containers which are rectangular or quadrangular in cross-section and thereby obviate the space loss resulting from the use of circular containers.

Another object of the present invention is to provide a paperboard or like container of the aforesaid type which is so manufactured that it can assume any desired wall thickness and is of a rectangular cross-section.

Another object of the invention is to provide means affording a relatively simple process for creating or winding the container body, abutments or indentations thereof for mounting a top closure ring and a bottom closure member.

Yet a further object of the present invention resides in the provision of means conducive to the construction of a very efficient container body presenting a shell or jacket of wound paper or like cellulosic material, which shell may be simultaneously provided during its manufacturing stage with peripheral recess or recesses, edges, flanges and like reinforcement parts, easily and readily incorporated in the shell or jacket.

Still another object of the present invention is to provide means facilitating anchorage or connection of hoops or similar ring-shaped elements of steel or like metal with the aforesaid shell or jacket, which may be made of wood veneer, cardboard, light-weight metal, plastic or plastic composition or a combination of such materials.

Other and further objects and advantages of the present invention will become apparent from a reading of the following description taken in connection with the drawing which illustrates the presently preferred embodiment of the invention.

In the drawing:

Fig. 1 is a vertical cross-section of a container pursuant to the present invention; and

Fig. 2 is a top plan view of the container seen in Fig. 1.

Referring now to the drawing in detail, there is shown a container or receptacle 20, which is rectangular in cross-section and which is especially well adapted for transporting or storing the contents thereof. The tubular or hollow body 1 of the container is wound or formed of relatively inexpensive sheet material to provide a seamless construction. For example, and not by way of limitation, the body may be formed of paperboard or sodium kraft paper which is wound about a rectangular form or

2

core to provide the desired thickness and rectangular cross-section for the container and to obviate the necessity for any body seam. At the upper end thereof, the body 1 terminates in an inwardly curved marginal portion 3 which forms a bead or rim at the upper end of the body 1. Adjacent the bead and below the latter, the body is provided with a peripheral indentation or groove 2, the function of which is hereinafter described in detail.

10 At the bottom thereof, the body is provided with a base including an inwardly extending bottom reinforcing rim 8 formed by bending or folding the body material inwardly upon itself, as best illustrated in Fig. 1. Immediately above the bottom rim 8, the body is provided with

15 a second peripheral groove or indentation 9, the function of which is hereinafter described in detail. It will be readily apparent to those skilled in the art that the indentations 2 and 9 may be formed during the winding of the body-forming sheet material about a previously 20 mentioned rectangular form (not illustrated).

A reinforcing ring 11, preferably formed of steel or other suitable metal, encompasses the upper end of the body 1. More specifically, the ring 11 is complementary to both the upper rim 3 and the upper indentation 2. The ring 11 is curled inwardly, as at 11a, to completely enclose the bead 3, and is inwardly bent or indented, as at 11b, so as to nest within the upper peripheral body indentation 2. A packing ring 4, of suitable resilient material, such as plastic or plastic composition, overlies the 30 ring 11, at the curled portion 11a thereof.

A dished cover 5, preferably made of steel, other sheet metal, wood, paperboard, or like suitable material, closes the body 1 at the top thereof. The cover has an arcuate peripheral flange 5a which overlies the packing ring 4.

35 The cover is secured in position by a tension ring 6, which serves to press the cover flange 5a downwardly toward the body rim 3. It will be noted that the tension ring also encompasses the upper portion of the securing ring 11, the bottom 6a of the tension ring extending into 40 the body indentation 2 and engaging under the overlying portion of the ring 11. Consequently, the tension ring 6 serves to clamp the cover 5 in position against the packing ring 4.

The lower end of the receptacle body 1 is closed by 45 a bottom member 7 preferably formed of steel or other suitable sheet metal. The member 7 is bent back upon itself and then curved upwardly to form the peripheral recess-defining portion 7a which encompasses the doubled-up bottom rim 8 of the body 1. The marginal edge 50 of the bottom 7 is defined by a curled extension portion 7b integral with bottom 7, said extension portion 7b being nested within the lower body indentation 9. A non-metallic disc 10, preferably formed of paperboard or 55 wood, is forced into position and covers the inner surface of the metal bottom 7 and serves as a liner or screen to prevent the deleterious effects of moisture so as to prevent damage to the body material.

It will be noted that the peripherally continuous body indentations 2 and 9, reinforced by the metallic members 60 11 and 7, respectively, on the outer surface of the body 1, and the relatively wide inwardly extending bottom rim 8, which is also metal-clad, impart an enhanced stability to the receptacle 20 which makes it possible to utilize a relatively thin wall thickness for the body 1 65 and thus save material. The wall thickness can vary with the size of the container.

As used in the annexed claims, the term "paperboard" comprehends generally kraft paper or cellulosic material. Various changes and modifications may be made without departing from the spirit and scope of the present 70 invention and it is intended that such obvious changes and modifications be embraced by the annexed claims.

Having thus described the invention, what is claimed as new and desired to be secured by Letters Patent, is:

1. A receptacle comprising a hollow body part having an upper and lower end and formed of paperboard, a first inwardly extending peripheral indentation defined adjacent the upper end of said body part, a second inwardly extending peripheral indentation defined adjacent the lower end of said body part, said body part having a rim located above said first indentation to facilitate mounting of a cover, said body part being provided with a base contiguous to said second indentation and located therebelow, said body part being rectangular in cross section, a cover securing tension member overlying said upper end and shaped for retainment in said first indentation, a cover for engaging said upper end and said tension member, a reinforcing member interposed between said cover and said upper end and encompassing the latter and extending into said first indentation for engagement by said tension member, when applied to said cover, a bottom closure extending across and engaged by said base, said bottom closure including a metallic member

having an extension portion integral therewith and encompassing said base to reinforce the latter, said extension portion projecting into and being retained in said second indentation, said metallic member completely closing said lower end, and a non-metallic disc overlying said metallic member and engaged between the latter and said second indentation.

2. A receptacle according to claim 1, said base including an inwardly extending bottom rim below and spaced from said second indentation, said disk and said metallic member being received and held between said bottom rim and said second indentation.
